UNITED STATES PATENT OFFICE.

LÜDER SCHRIEVER, OF DANZIG-LANGFUHR, FREE STATE OF DANZIG, AND ALFRED MICHAEL, OF BREMEN, GERMANY.

SHIP'S SIDE SCUTTLE.

Application filed January 27, 1927, Serial No. 164,063, and in Germany May 19, 1926.

In bad weather the side scuttles for the crew's quarters and cabins which are located on decks that are not at a high level, have to be kept closed, so the air in the cabins in question soon becomes bad.

Now there are already in use ships' side scuttles with ventilating devices wherein a casing is arranged over the glass holder. Through this casing the air from outside can enter the interior of the ship, and float valves are provided in the casing, and upon the water rising right above the level of the window, prevent the water from entering the interior of the ship. Such side scuttles, on account of the cases being fitted up with float valves of comparatively large diameters, are very large and cumbersome, look unattractive, and cannot be fitted in everywhere on account of Venetian blinds and curtains that may have to be provided. Since moreover the float valves are arranged in the immediate neighborhood of the aperture leading out of the casing into the interior of the ship it may happen that splashes reach the interior of the ship, particularly when the float valves are difficult to move, which may occur after some time owing to rust or dirt.

These defects are removed by the present invention, and a ship's side scuttle with a ventilating device is provided, which can be fitted up in any room and is not materially larger than an ordinary ship's side scuttle. A further advantage of the side scuttle construction according to the invention consists in the fact that the ventilating device employed admits of being adapted to side scuttles of any shape, quite irrespectively of whether they are round or angular, and that it is possible also to fit the ventilating device into already existing side scuttles.

The invention is illustrated by way of example in the accompanying drawings.

Figure 1 shows a sectional elevation through a ship's side scuttle according to the invention,

Figure 2 an outside view thereof,

Figure 3 a sectional elevation through a ship's side scuttle according to a somewhat different constructional form,

Figure 4 an outside view thereof,

Figure 5 a sectional elevation through another constructional form of the ship's side scuttle, and

Figure 6 an outside view thereof, partly in section.

In the drawings, A is a frame connected with the ship's wall, serving for fastening the ship's side scuttle. B is a metal member which forms a glass holder for the glass plate C, and in which at the same time the known packing is arranged.

According to the invention an air passage is provided in the side scuttle as an annular passage in one of the metal members surrounding the window pane, and closure elements are arranged in the lower part of this member. In the constructional example shown in Figure 1, such an annular passage D is provided in the metal member B immediately surrounding the glass disc C and serving as the setting thereof. In the lower part of this passage are provided outwardly leading apertures E, and as closure elements for these apertures balls F supported in front of them are arranged in a casing G. Under the resting place of the individual closure elements are arranged outwardly leading slots H in the casing G, which preferably run as nearly vertically as possible, as may be seen from Figure 2, so that the jets of water entering here quickly bring the closure elements on to their seats in the metal member B and hold them fast there.

In a particularly advantageous constructional form embodied in Figures 1 and 2, the closure elements are arranged in a special chamber I, or the casing forms a part of this chamber I, which is likewise constructed as an annular chamber and arranged in the metal member B surrounding the glass pane C. Upon the water entering, this chamber I acts as an air vessel, and helps, after the discharge of the water, owing to the air compressed in it, to bring the closure elements back into the open position and to expel the water that has forced its way in. In the case of the constructional example illustrated, the casing for the closure elements and the chamber I are formed by an annular member K, which screws into the part B. A ring L serves for holding the glass plate C.

In the upper part of the air passage D is provided an aperture M, which can be shut off at will by a sliding shutter N.

O is a known screen or deadlight completely shutting off the side scuttle.

In the constructional form according to

Figures 3 and 4 the annular passage D and the annular chamber I containing the closure elements are arranged with the slots H in a special metal member P, which is inserted 5 into the metal member B, which serves as a glass-holder. The member P is held fast in the member B by a ring Q, and the member P is divided in this case, for the insertion of the pane of glass C, preferably along 10 a line R.

Also in the case of this constructional form, in the upper part of the ship's window, namely in the part P, is provided a slot S, which can be closed at will by a sliding 15 shutter T.

In the constructional form according to Figures 5 and 6 the annular passage D and the annular chamber I are provided with the closure elements F and the slots H in the 20 window-fastening frame or window case, which is connected with the ship's wall and which for this purpose is preferably formed of two parts, namely a part U and a part U', which parts are pressed against one another 25 with the interposition of a packing. Here again in the upper part of the ship's side scuttle slots V are provided, which can be closed by sliding shutters W. Special passages X are provided, which open into a 30 chamber Y, so that the water passing out of the latter through the slots H into the annular chamber I lifts the balls F and is able to bring them on to their seats. In the case of this special construction a draining of 35 the chamber Y preferably takes place into the interior of the ship's hold, for example through a draining screw, tube or the like inserted at Z.

In the case of the constructional forms 40 according to Figures 1 and 2, as well as 5 and 6, the ventilating device is in operation even when the screen or deadlight O is closed.

The ship's side scuttle according to the 45 invention is of course not limited to side scuttles the glass-holders of which are opened but is also possible in a construction in which the setting for the pane of glass is rigidly connected with the frame secured to the 50 ship's hull.

What we claim is:

1. A ship's side scuttle, consisting in combination of a frame connected with the ship's hull, a pane of glass, metal members surrounding said pane of glass between said pane of glass and the frame on the ship's hull, said metal members being formed with air ducts therein, and with apertures on the inner side of the scuttle and in the upper 55 part of the metallic members, and with apertures on the outside thereof, said outside apertures being connected by said air ducts with the apertures first mentioned, and closure elements in these metal members for closing the apertures under the influence of 60

the pressure of the water outside the side scuttle.

2. A ship's side scuttle, consisting in combination of a frame connected with the ship's hull, a pane of glass, metal members surrounding said pane of glass, between said pane of glass and the frame on the ship's hull, said metal members being formed with air ducts therein, and with apertures on the inner side of the scuttle and in the upper 70 part of the metallic members, and with apertures in the lower part thereof, said lower apertures being connected by said air ducts with the apertures first mentioned, and closure elements in said metal members for 75 closing the last-mentioned apertures under the influence of the pressure of the water outside the side scuttle.

3. A ship's side scuttle, consisting in combination of a frame connected with the ship's hull, a pane of glass, a metal member surrounding and supporting said pane of glass between said pane of glass and the frame on the ship's hull, said metal member being formed with an annular air duct therein, and with apertures on the inner side and in the upper part thereof, and with conical apertures in the lower part thereof, said conical apertures being connected by said air duct with the apertures first mentioned, ball 85 shaped closure elements in the metal member for closing the conical apertures under the influence of the pressure of the water outside the side scuttle, and another metal member outside the side scuttle connected 90 with the metal member containing the apertures and forming with the first-mentioned metal member a casing for the ball-shaped closure elements and a special annular air space. 95

4. A ship's side scuttle, consisting in combination of a frame connected with the ship's hull, a pane of glass, a metal member surrounding and supporting said pane of glass between said pane of glass and the frame on the ship's hull, said metal member being formed with an annular air duct therein and with apertures on the inner side and in the upper part thereof, and with conical apertures in the lower part thereof, said conical apertures being connected by said air duct with the apertures first mentioned, ball-shaped closure elements in the metal member for closing the conical apertures under the influence of the pressure of the water outside the side scuttle, another metal member connected with the metal member containing the apertures and forming with the first-mentioned metal member a casing for the ball-shaped closure elements and a special 105 annular air space, and a further metal member enclosing the first-mentioned metal member and connecting it with the frame on the ship's hull. 110

5. A ship's side scuttle, consisting in com- 115

bination of a frame connected with the ship's hull, a pane of glass, a metal member surrounding and supporting said pane of glass between said pane of glass and the frame on the ship's hull, a metal member of angular cross section between said first-mentioned metal member and the frame on the ship's hull, said metal member of angular cross section being formed with an annular air duct therein, and with apertures on the inner side of the scuttle and in the upper part of the metal member, and with conical apertures in the lower part thereof, said conical apertures being connected by said air duct 10 with the apertures first mentioned, ball-

shaped closure elements in the metal member of angular cross section for closing the conical apertures under the influence of the pressure of the water outside the side scuttle, another metal member of angular cross section integral with the first-mentioned metal member of angular cross section, forming with the frame on the ship's hull a casing for the ball-shaped closure elements and a special annular air space. 20

25 In testimony whereof we have signed our names to this specification.

LÜDER SCHRIEVER.
ALFRED MICHAEL.
